UNITED STATES PATENT OFFICE.

CHARLES HAROLD HELME, OF PORTLAND, MAINE.

HEEL ATTACHMENT.

1,282,420.

Specification of Letters Patent. Patented Oct. 22, 1918.

Application filed February 13, 1917. Serial No. 148,865.

To all whom it may concern:

Be it known that I, CHARLES HAROLD HELME, a citizen of the United States, residing at Portland, in the county of Cumberland and State of Maine, have invented 5 certain useful Improvements in Heel Attachments, of which the following is a specification, reference being had therein to the accompanying drawing.

10 The invention relates to a heel attachment, and more particularly to the class of heel calk attachments for the heels of boots, shoes, or the like foot wear.

15 The primary object of the invention is the provision of an attachment of this character wherein the heel of a boot or shoe is materially reinforced, so as to prevent the heel from crushing or materially wearing away at the edges thereof, thereby increasing the 20 life of the heel.

25 Another object of the invention is the provision of an attachment of this character wherein the outermost lift or ply of the heel is materially reinforced, so as to increase the wear of the heel, and thereby sustaining the same straight, thus obviating the running over of the heels of boots or shoes, as is usual.

30 A further object of the invention is the provision of an attachment of this character wherein the entire heel, irrespective of the material from which the same is made, is materially strengthened, so as to give rigidity thereto, and thereby avoid the breaking down of the same, so as to assure neatness thereto, and avoid the running over of the heel, or the shoe becoming out of shape resultant therefrom.

35 A still further object of the invention is 40 the provision of an attachment of this character which possesses simplicity in construction, reliability and efficiency, durability, strength, and also one which is inexpensive in manufacture.

45 With these and other object in view, the invention consists in the features of construction, combination, and arrangement of parts, as will be hereinafter fully described, 50 illustrated in the accompanying drawing, and pointed out in the claim hereunto appended.

In the accompanying drawing:

Figure 1 is a fragmentary bottom plan view, showing a shoe heel by full lines, and 55 the attachment constructed in accordance with the invention applied, by dotted lines.

Fig. 2 is a fragmentary vertical longitudinal sectional view of the heel plate.

Fig. 3 is a perspective view of the heel plate. 60

Fig. 4 is a perspective view of one of the calks.

Similar reference characters indicate corresponding parts throughout the several views in the drawings. 65

Referring to the drawings in detail, A designates generally a shoe heel which is usually made up from a plurality of plies 5, preferably leather, although the same may be made from any other substitute material, the said heel being constructed in the usual well known manner, and is merely shown to illustrate the application and manner of use of the attachment hereinafter fully described. 70

The ply 6, next to the outermost ply 7 of the series 5 of the heel, is cut to form a counter-sink 8 for receiving a frame 9, forming a reinforcing plate, which is preferably made from metal, and is provided with an open center 10, which may be of the required shape and which serves as a cell between the outermost ply 7 and the ply 8 next thereto of the heel, thereby assuring a determined 75 amount of resiliency to the heel.

80 Mounted in the heel A, through the inner face thereof, is a series of calks, each comprising a stem 11, formed with a head 12 at one end, while the opposite end is reduced to form a rivet terminal 13, and these calks are inserted within the heel A in suitable openings therefor, formed in the plies 5 of said heel from the inner side thereof, the heads 12 being fitted in correspondingly shaped 85 counter-sinks 14 formed in the innermost ply, while the reduced ends 13 are passed through apertures 15 formed in the frame 9, and are riveted thereto prior to the fastening of the outermost ply 7 in place, as will be clearly obvious, the counter sink 8 is correspondingly shaped to the plate 9 for accommodating the same, which is concealed by the outermost ply 7 of the heel when said ply is fastened in place, as is clearly 90 shown in Fig. 2 of the drawing.

95 The heads 14 of the studs abut and contact with the heel end of the sole B of the shoe, as is also clearly shown in Fig. 2 of the drawing, and by the use of these studs and the plate of frame 9, the heel of said shoe is materially reinforced, and is prevented from breaking down. 100

105 The heads 14 of the studs abut and contact with the heel end of the sole B of the shoe, as is also clearly shown in Fig. 2 of the drawing, and by the use of these studs and the plate of frame 9, the heel of said shoe is materially reinforced, and is prevented from breaking down. 110

It will be noticed that substantially four studs are employed and these studs are arranged adjacent to the rim of the heel as is clearly shown in Fig. 1. The pressure applied by the foot down upon the heel of the shoe is transmitted to all of the studs and the shoulders of said studs apply a downward pressure on the plate 9 which is flat and stiff and tends to keep the heel in engagement with the surface it engages.

Numerous modifications may be made in practice without departing in principle from the details of construction herein disclosed.

What is claimed is:

15 In a shoe, in combination, a plurality of leather heel layers, the innermost layer being formed at its four corners with countersunk outwardly flaring recesses, the next to the last layer being formed with a coun-

tersunk cavity, a heel-shaped plate formed 20 with a large central opening so as to provide a perimetrical strip of uniform width, said plate being formed with four relatively small openings, and fitting snugly within the cavity of said second mentioned layer, a series of locking bolts each consisting of a conical head embedded in one of said first-named recesses, and a main body portion projecting into all of said layers and terminating in a reduced portion projecting 30 through one of said small openings, and being capped so as to overlie said plate to lock all of said layers together, and another leather layer secured so as to overlap and conceal said plate, said bolts having shoulders engaging the inner side of said plate.

In testimony whereof I affix my signature.

CHARLS HAROLD HELME.
